TOY

Joseph Lowell and Bernhardt C. Berg,
Los Angeles, Calif.

Application July 2, 1945, Serial No. 602,724

1 Claim. (Cl. 46—43)

Our invention relates to that class of inventions which are primarily designed as a toy for the amusement of children, but it is also intended to have an educational purpose in that it demonstrates some of the elementary principles of mechanics. It illustrates the action of gravity; wheel and axle, counter-weight walking beam and the effect of changing the center of gravity.

We illustrate our invention by means of the accompanying drawing, in which similar numerals refer to similar parts in the several views. Figure 1 is a vertical central section of the device, the dot-dash lines showing the bucket in the discharge position. Figure 2 is a front elevation. Figure 3 is a cross-section taken on the line 2—2 of Figure 2. In the design illustrated the column 10 and the base 11 are integral, but the manufacturing cost might be reduced by making them separate and secured to each other. Figure 4 is a perspective view of the bucket.

The construction of our device is as follows: 10 is an upright column having a base 11. The column and base are preferably made in one piece, but if desired can be made in two parts glued or otherwise fastened together. 12 is a passage-way or central hollow core within the said column and base. This passage-way is approximately vertical and parallel with the said column, but it describes a semi-circular path as it passes through the base 11. This passage-way 12, and its curved portion 14 is adapted to receive therein a plurality of balls 13, for a purpose which is more fully hereinafter described. The balls are introduced into the passage-way 12 through the opening 15 where the passage-way emerges from the base 11. Means are provided for preventing the balls from running back and out of the passage-way. This can be accomplished in several ways, but in the forms illustrated a check-spring 16 is located in the passage-way 14. This check-spring allows the balls to pass into the passage-way and prevents their return. The balls are introduced into the passage-way by manual pressure, or by a blow, such as that given by a mallet. Near the upper end of the column 10, the vertical part of the passage-way is closed by a downwardly directed discharge passage-way 19 which extends from this main passage-way through the front wall of the column 10. Located in the passage-way 12 at its junction with the passage-way 19 there is secured a "soft" spring 20 which limits the movement to one ball for each blow or each manual pressure.

Journalled on the shaft 38 in an extension of the column 30 and operating in the slot 21 is the

sheave 22, over which travels the cord 23. One end of this cord is connected to a bucket 25 by means of the bail 26. The bucket is triangular in shape and of a size that will contain one ball 13. Attached to the other end of the cord 23 is a counter-weight 31. The cord 23 is held within limits by passing through the guide 27. To still further guide and control the movement of the bucket the column 11 is provided with a T-shaped slot located on its face and adapted to receive the pins 18 which together with the bucket travel up and down in the said slot. On the descending movement of the bucket the said pins finally reach the bottom of the slot at the point 39 and the further movement of the bucket consists of a tipping fulcrummed on the said pins and causing the ball to be discharged whence it rolls down the ramp 29 and in position to repeat the cycle.

The spring 20 wraps itself around the top ball 20 of the column of balls, for the purpose of limiting the action to one ball at a time. When the top ball reaches the spring 20 the action of the spring causes the center of gravity to move forwardly as the ball is pushed upwardly, causing the top ball 20 to roll down the passage-way 19 and into the bucket 25. The weight of the ball added to that of the bucket causes the bucket 25 and the ball 13 to fall by gravity to the base 11. The bucket 25 is provided with pins 18 on its inner corners and these pins travel in the T-slot 37, guiding the bucket to the base and when the said pins reach the bottom of the slot 37 at 39 they act as a fulcrum and they upset the bucket, which allows the ball to roll out onto the ramp 29 in position ready to be re-entered through the opening 15. This is accomplished by the application of manual pressure. The bucket with its weight reduced is then drawn up by means of the counterweight 31 and the cord 23, into the discharge position opposite the passage-way 19.

What we claim as our invention and desire to secure by Letters Patent is:

In a device of the class described, the combination of an upright column having a passage-way 45 there-through and adapted to contain a plurality of balls, one above another together with ball entering and ball discharging passage-ways; a yieldable check-spring in said ball entering passage-way; the ball entering passage way being 50 in the form of a reverse curve communicating with the column passage so that manual force causes each ball to enter, one at a time through the said check spring into the upright passage way to enter, one at a time through the said 55 check-spring into the upright passage-way and

to move upwardly therein; means for carrying the balls also one at a time from the said discharge passage-way to the said ball entering passage-way, said means consisting of a bucket so shaped and so positioned as to receive the ball emerging from the said ball discharging passage-way, said ball and bucket falling by gravity to said check-spring; means for returning said bucket to said

discharge passage-way, said means comprising a sheave revolvably mounted on said column, a counter-weight of sufficient weight as to lift the empty bucket, said bucket and said counterweight being connected by a cord running over said sheave
